Daniel Hale

The schedule referred to in these Letters Patent and making part of the same containing a description in the words of the said Daniel Hale himself of his improvement in the machine for rolling and cutting crackers

The first consists of a frame standing on four posts, the frame may be about six feet long and the width adjustable to the number of cutters should be put in the machine, the height from three to four feet, the posts at one end of the machine which is called the head, extend from two to three feet above the sides of said frame, where the slide works, in that the cutters are attached to, these posts are on a pitch of about fifteen degrees, there are two rollers being in two short posts back of the other four posts, one roller above the other, which roll the dough, this dough is brought on by an ^{thin} apron, gets its motion by means of two small rolls one of them let into the sides close to the rollers that roll the dough, and the other at the back end, this apron is about four feet long and moves with motion from the roller that roll the dough by means of bands and small pulleys, the dough passes through the rollers on a platform of lead where the cutters cut the crackers, this platform of lead is lead with the lower roller that roll the dough, there is another apron that takes the crackers from this platform which is about three feet long and is covered by rollers, the same as the other apron and gets its motion from the roller that roll the dough in the same way as the other apron, the cutters are put on a plate

plate in a slide similar to a draw gate which works up and down in these posts at the head, these cutters get their motion from a shaft which passes thro' under the platfrom with the cranks at each end & piston to connect the cranks and slide together, the rollers get their motion from this piston by being two pulleys put one at each end of the upper roller. That rolls the dogh with cogs on them and bands round them, which work loose and a catch in one side of the bands which catch in these cogs, there is a handle in one side of these bands which runs out to the piston and is connected to them and when the cutter raise it gives motion to the rollers and when the cutter go down the rollers stand still, these cutters may be put on brass or any other metallic substance in one two or three rows together in any number from one to fifty or more.

The bushes for these cutters are screwed in through the plate any number may be put in, there are small plates put in for cleavers which get their motion by having two small wires riveted in each side of the plate and bushes thro' the plate that the cutters are placed into a slot in which fixed in by ^{means} of small bushes, this is done each end when the cutters go down just before they come in to cut and when the cleavers up in the cutter, and when the cutters raise, the cleavers move out by means of a spring and when the cutters go back out, this move is put in the centre of the cutter and it goes up through the plate & small bushes on the opposite side, this move has no motion but as fast as for the movement.
